UNITED STATES PATENT OFFICE.

JOHN B. JOBSON, OF ATLANTA, GEORGIA.

DESIGN FOR A SCARF-PIN OR SIMILAR ARTICLE.

SPECIFICATION forming part of Design No. 24,723, dated October 1, 1895.

Application filed July 12, 1895. Serial No. 569,778. Term of patent 3½ years.

To all whom it may concern:

Be it known that I, JOHN B. JOBSON, a citizen of the United States, residing at Atlanta, in the county of Fulton and State of Georgia, have invented and produced a new and original Design for a Pin or Similar Article of Manufacture; and I do declare the following to be a full, clear, and exact description of the same, reference being had to the accompanying drawing, forming a part thereof.

In the accompanying drawing the figure is an elevation of a pin, showing my design.

The leading feature of my design consists of a pin or similar useful article of manufacture having a head made in the form of and resembling an open cotton boll.

A indicates the pin and B the head thereof, which is suitably connected to the pin. The said head B is in outline of a general oval shape and the edge of its lower portion C is

fluted, while the surface of such lower portion is lined or marked, as shown, to represent raw cotton. The upper portion D of the head B is round on its upper edge and on its lower edge has the petals E, tapering toward their ends, so as to represent the burr of a cotton boll. From such upper portion D there extends a reduced curved portion F, which is designed to represent the stem of the cotton boll and rests without the oval outline, as shown.

What I claim is—

The design for a pin, substantially as herein shown and described.

In testimony whereof I affix my signature in presence of two witnesses.

JOHN B. JOBSON.
